UNITED STATES PATENT OFFICE.

CHARLES STANLEY RHOADS, JR., OF SANDWICH, ILLINOIS, ASSIGNOR, BY MESNE ASSIGNMENTS, TO HALL SWITCH & SIGNAL COMPANY, A CORPORATION OF MAINE.

SIGNAL-RECEIVING DEVICE.

1,105,837.

Specification of Letters Patent.

Patented Aug. 4, 1914.

Application filed August 8, 1911. Serial No. 642,951.

To all whom it may concern:

Be it known that I, CHARLES STANLEY RHOADS, Jr., a citizen of the United States, residing at Sandwich, in the county of De-
5 kalb and State of Illinois, have invented a certain new and useful Improvement in Signal-Receiving Devices, of which the following is a full, clear, concise, and exact description, reference being had to the accompanying drawings, forming a part of
10 this specification.

My invention relates to substation receiving devices for use in signaling systems and more particularly to the arrangement of receiving devices in systems of the character in which impulses are utilized to select a particular substation instrument for signaling purposes. In the specific form of the device herein, it is arranged for selective
15 operation and the construction is such that actuating and release impulses may be used to carry out the functions desired.

It is the prime object of my invention to arrange a substation device of this character in such a way that auxiliary signal circuit control contacts are provided in addition to the signal circuit control contacts directly controlled by a step-by-step element when such is utilized in connection with my
20 invention.

In the preferred form of the invention, I utilize preferably a polar relay which through the agency of a local battery is adapted to control a step-up magnet and
25 the release magnet, both of which are associated with a step-by-step element. A sluggish relay is also associated with the magnets aforesaid and controls a contact which controls the signal circuit of the substation.

40 I will explain my invention more in detail by reference to the accompanying drawing illustrating a system arranged in accordance with my invention. In this illustration I show a central station A and sub-
45 stations B, C and D. A line circuit preferably consisting of the two line wires 1 and 2 unites all of the stations together.

At the central station I have two keys 3 and 4 respectively, of which key 3 is adapted
50 to send impulses of a given character from the battery 5 over the line wires 1 and 2, and key 4 is adapted to send impulses of a reverse polarity by means of the battery 6 over the same line wires. The keys 3 and 4 are merely indicative of automatic sending

mechanism which may be employed and are merely set forth as means for sending impulses of different characters. At each substation I have a polar relay 7 bridged across the line wires 1 and 2, which polar relay has 60 an armature 8 normally in its central position, but adapted when actuated in one direction to engage the contact 9 and when actuated in the other direction to engage the contact 10. A battery 11 has one terminal thereof preferably connected with said armature to furnish the current when said armature contacts with either contact point 9 or 10. The contact 9 is connected by means of a conductor 12 with the winding of a step-up magnet 13 and a conductor 14 continues the connection to a sluggish relay 15 from whence a conductor 16 completes the circuit of the battery 11. The contact point 10 is connected by means of a conductor 17 to the winding of a release relay 18 from which the circuit extends by means of a conductor 19 to the conductor 14, thence through the winding of the sluggish relay 15 and conductor 16 back to the battery 11. 75

A step-by-step element 20 having a pointer 21 is controlled by a pawl 22, which pawl is actuated by the armature 23 of the magnet 13. A holding pawl 24 is employed the function of which is obvious. 80 The release relay 18, by virtue of its armature 25 and arm 26, serves, when actuated, to disengage both pawls 22 and 24 from the teeth of the element 20 to thereby permit the return of said element 20 against its 90 stop 27, through the agency of the spring 28. The pointer 21 is adapted to engage a contact 29 which is directly connected with a local signal 30, the circuit from there being continued by means of the conductor 31 to one pole of the battery 11. This circuit further extends from the other terminal of said battery through the conductor 16, contact 33, armature 34, conductor 35 to the arm 21 of the step-by-step element 20. 95 A spring 35' normally maintains a closure of the circuit between the armature 34 and contact 33.

Now when, say, positive impulses are transmitted over the line wires 1 and 2, 105 armature 8 engages contact 9, thereby energizing magnet 13 which actuates the armature 23 to step-up the element 20. Should these impulses cease, the elements 20 remain in the position last occupied until an 110

impulse of negative polarity is transmitted over the line wires, at which time the armature 8 engages contact 10, thereby energizing the magnet 18 which attracts its armature 25, thereby disengaging pawls 22 and 24 from the teeth of the element 20 so that it may return to normal.

It will be seen that all of the impulses transmitted through the magnet 13, also the 10 impulse or impulses transmitted through the magnet 18 pass serially through the relay 15. Now the first step-up impulse transmitted actuates not only the magnet 13, but also the relay 15 which is sluggish only so 15 far as release is concerned, and which therefore draws up its armature promptly upon initial energization. This first impulse therefore breaks the contact between the armature 34 and the contact 33 and opens 20 at each substation the signal circuit. The arms 21 of the various step-by-step elements occupy different angular positions so that each substation answers to a number of impulses different from its companion stations. 25

Now assuming that a sufficient number of positive impulses have been transmitted to bring the arm 21 of the substation B into engagement with the contact 29, the signal 30 circuit is completed at this contact at this particular station. The signal circuit however is open at contact 33 and would remain open if succeeding impulses were sent with such a short time interval between 35 them that the relay 15 did not have time to release. If the impulses however are discontinued immediately the arm 21 engages the contact 29, then no current is present in either the magnets 13 and 18 or the relay 40 15 and if the discontinuance of the impulses is long enough, armature 34 is released and closes the signal circuit at all of the stations, but the signal 30 of substation B only will respond as the arm 21 of that particular 45 station alone is in association with its associated contact. It will thus be seen that the signal circuit is finally made at the contact 33. This is a great advantage because the adjustment of the arm 21 need not 50 then be so accurate as heretofore. Now after the signal has operated a sufficient length of time, an impulse of reverse polarity is transmitted from the central station and this operates the magnet 18 and 55 the relay 15, whereby the relay 15 opens the signal circuit at the contact 33 so as to avoid any sparking between the arm 21 and its associated contact 29. The contact 33 in association with the armature can be 60 better constructed to accommodate any sparking than can the movable arm with its associated contact. Controlling the signal circuit at the contact 33 also gives another advantage, namely that in stepping 65 past a contact 29, for instance, when a sta-

tion beyond the one under consideration is being called, the bell 30 does not tap because the signal circuit is open at contact 33. This is also true when the release impulse is sent because the signal circuit is open at 70 the contact 33 before the elements begin to move in the reverse direction.

The various advantageous features of my improved substation signal receiving device will thus be apparent and while I have 75 described herein one embodiment which my invention may take, I do not so limit myself as my invention may be broadly applied and is also susceptible of many modifications.

Having however, thus described one embodiment of my invention, what I claim as new and desire to secure by Letters Patent is:

1. A signal receiving device having a 85 step-by-step element, electro-magnetic step-up means for said element, electromagnetic release controlling means for said element, a signal circuit controlled by said element, and electromagnetic means for closing said 90 signal circuit upon cessation of the impulses subsequently to the initial circuit closure by said element.

2. A signal receiving device having a 95 step-by-step element, electromagnetic step-up means for said element, electromagnetic release controlling means for said element, a signal circuit controlled by said element, and means to render said signal circuit inoperative during the release movement of 100 said element after said element has been stepped past its circuit closing position.

3. A signal receiving device having a 105 step-by-step element, electromagnetic step-up means for said element, electromagnetic release controlling means for said element, a signal circuit controlled by said element, and electromagnetic means operable upon 110 cessation of impulses for closing said signal circuit subsequently to the control by said element.

4. A signal receiving device having a 115 step-by-step element, electromagnetic step-up means for said element, electromagnetic release controlling means for said element, a signal circuit controlled by said element, and electromagnetic means operable con- 120 jointly with said step-up and release controlling means for controlling said signal circuit.

5. A signal receiving device having a 125 step-by-step element, electromagnetic step-up means for said element, electromagnetic release controlling means for said element, a signal circuit controlled by said element, and sluggish electromagnetic means for closing said signal circuit upon cessation of the impulses subsequently to the circuit closure thereof by said element.

6. A signal receiving device having a 130

- step-by-step element, electromagnetic step-up means for said element, electromagnetic release controlling means for said element, a signal circuit controlled by said element, 5 electromagnetic means for closing said signal circuit upon cessation of the impulses, a local source of current and electromagnetic means for associating said source with said three aforesaid electromagnetic means.
- 10 7. A signal receiving device having a step-by-step element, electromagnetic step-up means for said element, electromagnetic release controlling means for said element, a signal circuit controlled by said element, 15 electromagnetic means for closing said signal circuit upon cessation of impulses, a local source of current and a polar relay for associating said source with said three aforesaid electromagnetic means.
8. A signal receiving device having a step-by-step element, electromagnetic step-up means for said element, electromagnetic release controlling means for said element,
- a signal circuit controlled by said element, and electromagnetic means to render said signal circuit inoperative during the release movement of said element after said element has been stepped past its circuit closing position. 25
9. A signal receiving device having a step-by-step element, electromagnetic means to control the operations of said element, means for moving said element to initial position when released, a signal circuit controlled by said element, and additional 30 means to render said signal circuit inoperative during the release movement of said element after said element has been stepped past its circuit closing position.
- In witness whereof, I hereunto subscribe 40 my name this 17th day of July, A. D., 1911.
